No. 840,751.

PATENTED JAN. 8, 1907.

R. J. COOK & H. H. HARVEY.
GRAIN CAR DOOR.
APPLICATION FILED MAR. 8, 1906.

Fig. 1

UNITED STATES PATENT OFFICE.

ROY J. COOK AND HILLMAN H. HARVEY, OF CHICAGO, ILLINOIS.

GRAIN-CAR DOOR.

No. 840,751.

Specification of Letters Patent.

Patented Jan. 8, 1907.

Application filed March 8, 1906. Serial No. 304,825.

To all whom it may concern.

Be it known that we, ROY J. COOK and HILLMAN H. HARVEY, citizens of the United States, residing in Chicago, in the county of Cook and State of Illinois, have invented a new and useful Improvement in Grain-Car Doors, of which the following is a specification.

Our invention relates to improvements in doors for grain-cars.

The object of our invention is to provide a grain-car door of a simple, efficient, strong, and durable construction capable of being easily and conveniently released or opened.

Our invention consists in the means we employ to practically accomplish this object or result—that is to say, it consists, in connection with the main door upon which our release or supplemental door is ordinarily mounted having an opening to receive the release-door and provided with strips or keepers at the ends thereof adapted to engage and hold the outer ends of the release-door in place, while permitting them to move toward each other to free themselves from such overhanging strips or keepers, of a release-door comprising two sections or members hinged together at their meeting ends and connected at their upper edges by sliding two-way hinges to the main door, one of the hinged sections of the release-door having an outer projecting handle member overlapping the hinge connecting the two sections and the other section being provided with a fastening and releasing device engaging said projecting handle member, whereby when the handle member is unfastened or released the two sections of the release-door may swing outward at their middle until the opposite ends are withdrawn or retracted from the strips or keepers on the main door, and then the release-door may be swung upward against the main door or part upon which it is mounted, the two-way hinge which connects the release-door with the main door permitting first the outward or horizontal swinging movement and then the upward or vertical swinging movement and the sliding of the members of the two-way hinges upon each other permitting or accommodating these movements.

Our invention further consists in the novel construction of parts and devices and in the novel combinations of parts and devices herein shown and described.

In the accompanying drawings, forming a

part of this specification, Figure 1 is a side elevation of a grain-car door embodying our invention and showing a portion of the car to which it is applied. Fig. 2 is a view, partly in vertical longitudinal section and showing the door in elevation from the inside. Fig. 3 is an enlarged horizontal detail section on line 3 3 of Fig. 1. Fig. 4 is a similar view showing the grain-door partly opened and its opposite ends almost retracted or withdrawn from the strips or keepers on the main door. Fig. 5 is a detail vertical section on line 5 5 of Fig. 3.

In the drawings, A represents a portion of a grain-car having an opening A' therein closed by the main door B, which is or may be of any suitable or desired construction known to those skilled in the art. The door is preferably a vertically-sliding and inwardly-swinging one, moving up and down on the guides or rods B' and having metallic guides or loops b attached to the door to engage the rods B'.

The main door B has an opening C therein, which is closed by the supplemental or release door D, and the main door is also provided with guide strips or keepers B², which overlap and engage the ends of the release-door when the same is closed and hold the same in position.

The release-door D comprises two hinge sections or members d d, connected together at their meeting ends by a hinge d', the axis or pintle d² of which is upright. The sections or members d d are preferably made of equal lengths, so that the hinge d' will come at the middle of the release-door, although the sections may be made of unequal length, if desired. Each of the sections d of the release-door is hinged at its upper edge and near its outer end to the main door B by a two-way hinge F, preferably comprising a pin or bolt f, having an upright arm f', fitting in a strap f², secured to the main door, and a horizontal arm f³, fitting in the hinge-strap f⁴, secured to the grain-door section d, the strap f⁴ being adapted to slide on the arm f³ to accommodate the two-way swinging movements of the door-section. The right-angle hinge-bolt f has at one end a head f⁵ and at its other or horizontal end a washer f⁶ and cotter-pin f⁷ for preventing the release-door section d from becoming disengaged. The release-door D is also provided with a projecting handle member d³, secured to one of the sections d of the door and pro-

jecting beyond the hinge $d' d^2$, which connects the meeting ends of the door-sections $d d$. This handle member d^3 is furnished with a handle d^4 and with a slot d^5 to receive the fastening and releasing device d^6 , which is secured to the other or companion door-section d , this releasing device consisting, preferably, of a bolt with a right-angle arm or handle d^7 for turning the same.

10 In operation, the door being in its closed position, as represented in Figs. 1 and 3, the fastening or releasing device d^6 is simply turned to bring its arm d^7 parallel with the slot d^5 in the handle member d^3 and then 15 the pressure of the grain against the door from the inside swings the door outward, the two sections $d d$ turning on the hinge, which connects their meeting ends, and also on the upright arms of the hinge F , 20 which connects the release-door with the main door, the release-door being thus pushed or pulled outward until its opposite ends are retracted or withdrawn from the keepers, flanges, or strips B^2 on the main door, the hinge-straps f^4 sliding on the horizontal arm f^3 of the two-way hinge to permit this, and then the release-door may be swung 25 vertically upward against the main door, the sliding of the members of the two-way 30 hinges $F F$ then permitting the two sections of the release-door to resume their normal or straight position.

The release-door D serves when opened to relieve the pressure of the grain against the 35 main door or grain-door proper, B , and thus enables it to be easily and conveniently raised. At the same time by our novel construction and combination of parts the release-door is firmly and securely held in its 40 closed position and can also be very easily released by simply turning the fastener d^6 .

We claim—

1. In a grain-car door, the combination with the main door, having an opening to receive a release or supplemental door, and provided with guide strips or keepers therefor, of a release or supplemental door comprising two sections hinged together at their meeting ends, two-way hinges having sliding 50 members connecting said release or supplemental door with the main door, one of the sections of the release or supplemental door being provided with a projecting or overlapping member, and the other with a fastening and releasing device engaging said overlapping or projecting member, substantially as specified.

2. In a car, the combination with a vertically-sliding and inwardly-swinging main door, having a supplemental-door opening therein, and provided with guides or keepers at the ends of said opening to engage the outer ends of the supplemental door, of a horizontally and vertically swinging supplemental door composed of two sections hinged

together at their meeting ends, and two-way hinges having sliding members connecting said supplemental door with the main door, substantially as specified.

3. In a car, the combination with a vertically-sliding and inwardly-swinging main door, having a supplemental-door opening therein, and provided with guides or keepers at the ends of said opening to engage the outer ends of the supplemental door, of a horizontally and vertically swinging supplemental door composed of two sections hinged together at their meeting ends, and two-way hinges having sliding members connecting said supplemental door with the main door, one of the hinged sections of the supplemental door having an outer overlapping handle member and a fastening and releasing device for connecting the overlapping handle member with the other section of the supplemental door, substantially as specified.

4. The combination with guides or keepers B^2 to engage and hold in position the opposite ends of the door D , of the door D comprising two sections hinged together at their meeting ends to enable the door to swing horizontally outward sufficiently at its middle to retract or withdraw the ends of the door from said guides or keepers B^2 and two-way hinges having sliding members upon which the door is mounted to enable it to swing both horizontally and vertically, substantially as specified.

5. The combination with guides or keepers B^2 to engage and hold in position the opposite ends of the door D , of the door D comprising two sections hinged together at their meeting ends to enable the door to swing horizontally outward sufficiently at its middle to retract or withdraw the ends of the door from said guides or keepers B^2 and two-way hinges having sliding members upon which the door is mounted to enable it to swing both horizontally and vertically, the members of said two-way hinges having a sliding movement upon each other.

6. The combination with guides or keepers B^2 to engage and hold in position the opposite ends of the door D , of the door D comprising two sections hinged together at their meeting ends to enable the door to swing horizontally outward sufficiently at its middle to retract or withdraw the ends of the door from said guides or keepers B^2 and two-way hinges having sliding members upon which the door is mounted to enable it to swing both horizontally and vertically, one of the sections of said door having an overlapping handle member, and a fastener for connecting said handle member with the other section, substantially as specified.

7. The combination with guides or keepers B^2 to engage and hold in position the opposite ends of the door D , of the door D comprising two sections hinged together at their

meeting ends to enable the door to swing horizontally outward sufficiently at its middle to retract or withdraw the ends of the door from said guides or keepers B² and two-way 5 hinges upon which the door is mounted to enable it to swing both horizontally and vertically, the members of said two-way hinges having a horizontally - sliding movement upon each other, one of the sections of said 10 door having an overlapping handle member, and a fastener for connecting said handle member with the other section, substantially as specified.

8. The combination with a door comprising two sections hinged together at their 15 meeting ends, of two-way hinges F having horizontally - sliding members upon which the door is mounted, substantially as specified.

9. The combination with a door comprising two sections hinged together at their meeting ends, of two-way hinges F having horizontally - sliding members upon which the door is mounted, said two-way hinges 20 having a pin or pintle member provided with upright and horizontal arms, substantially as specified.

10. The combination with a door comprising two sections hinged together at their 25 meeting ends, of two-way hinges F having horizontally - sliding members upon which the door is mounted, said two-way hinges

having a pin or pintle member provided with upright and horizontal arms, and a hinge-strap secured to the door-section sliding on the horizontal arm of the pin or pintle member, substantially as specified. 35

11. The combination with a door comprising two sections hinged together at their meeting ends, of two-way hinges F having horizontally - sliding members upon which the door is mounted, one of the sections of said door having an overlapping handle member, and the other a fastening and releasing device to engage said overlapping handle 40 member, substantially as specified. 45

12. The combination with a door comprising two sections hinged together at their meeting ends, of two-way hinges F having horizontally - sliding members upon which the door is mounted, one of the sections of said door having an overlapping handle member, and the other a fastening and releasing device to engage said overlapping handle member, said overlapping handle member 50 having a slotted end to engage said fastening and releasing device, substantially as specified. 55
